United States Patent Office

Des. 203,141
Patented Dec. 7, 1965

203,141

HOUSING FOR A COMPUTING MACHINE

Robert K. Yagura, Seabrook, N.J., assignor to Monroe International Corporation, Orange, N.J., a corporation of Delaware

Filed Jan. 26, 1965, Ser. No. 83,587

Term of patent 14 years

(Cl. D64—11)

FIG. 1

FIG. 2

FIG. 3

FIG. 4

FIG. 1 is a right side elevational view of the housing for a computing machine.

FIG. 2 is a top plan view thereof.

FIG. 3 is a front elevational view thereof.

FIG. 4 is a rear elevational view of the housing.

The essential features of the design reside in the portions shown in solid lines.

I claim:

The ornamental design for a housing for a computing machine, as shown and described.
